(57) **CLAIM**

The ornamental design for a combined dispenser container and handle for an applicator, as shown and described.

DESCRIPTION

FIG. 1 is an exploded in perspective view of a combined dispenser container and handle for an applicator showing our new design;

FIG. 2 is a top plan view of the dispensing container;

FIG. 3 is a bottom plan view thereof;

FIG. 4 is a side elevational view thereof, taken along line 4-4 of FIG. 2;

FIG. 5 is a side elevational view thereof, taken along line 5-5 of FIG. 2;

FIG. 6 is a side elevational view thereof, taken along line 6-6 of FIG. 2;

FIG. 7 is a top plan view of the handle of the combined dispenser container and handle for an applicator;

FIG. 8 is a bottom view thereof;

FIG. 9 is a side elevational view thereof, taken along line 9-9 of FIG. 8;

FIG. 10 is a side elevational view thereof, taken along line 10-10 of FIG. 8;

FIG. 11 is a side elevational view thereof, taken along line 11-11 of FIG. 8.

FIG. 12 is an exploded perspective view of the combined dispenser container and handle for an applicator shown in environmental use; and,

FIG. 13 is a perspective view thereof, with the handle shown connected to the dispenser container.

The broken lines shown represent unclaimed subject matter and form no part of the claimed design.
